United States Patent Office

Des. 195,000
Patented Apr. 9, 1963

195,000

BOTTLE OR SIMILAR ARTICLE

Morton Goldsholl, 800 Kimballwood Lane,
Highland Park, Ill.

Filed Jan. 2, 1962, Ser. No. 68,153

Term of patent 14 years

(Cl. D58—6)

Fig. 1.

Fig. 2.

Fig. 3.

Fig. 4.

The rear elevational view is substantially the same as the front elevational view.

I claim:

The ornamental design for a bottle or similar article, substantially as shown and described.
